United States Patent

Des. 241,291
Patented Sept. 7, 1976

241,291

BED

Giovanni Offredi, Milan, Italy, assignor to Fratelli Saporiti, Besnate, Varese, Italy

Filed Mar. 18, 1974, Ser. No. 452,415

Claims priority, application Italy Sept. 21, 1973

Term of patent 14 years

Int. Cl. D6—01

U.S. Cl. D6—80

FIG. 1.

FIG. 2.

FIG. 3.

FIG. 5.

FIG. 4.

FIG. 1 is a perspective view of a bed showing my new design;

FIG. 2 is a left side perspective view with the head lamps moved 90° toward the front of the bed;

FIG. 3 is a front elevational view with the head lamps in the position of FIG. 1;

FIG. 4 is a bottom plan view with the structure which would be seen through the bedsprings omitted for convenience of illustration; and

FIG. 5 is a fragmentary partial rear and left side perspective view with the side tables in retracted position and the head lamps moved 90° down from their position in FIG. 1.

What I claim is:

The ornamental design for a bed, substantially as shown and described.
